UNITED STATES PATENT OFFICE.

IRA E. CLUM, OF LIMA, OHIO, ASSIGNOR OF ONE-HALF TO THE MARTIN STEEL PRODUCTS CO., OF MANSFIELD, OHIO.

METAL FENCEPOST.

1,356,970.

Specification of Letters Patent. Patented Oct. 26, 1920.

Application filed December 10, 1919. Serial No. 343,848.

To all whom it may concern:

Be it known that I, IRA E. CLUM, a citizen of the United States, residing at Lima, in the county of Allen and State of Ohio, have 5 invented a new and useful Metal Fencepost, of which the following is a specification.

This invention relates to metallic fence posts, one of its objects being to provide a post which is made of sheet metal and has 10 simple and efficient means for connecting the fence fabric thereto without the use of fastening wires, clips, bolts or the like, the construction of the fabric engaging means being such that it is impossible for stock to 15 detach the fabric from the post by pushing upwardly or downwardly thereon or by pulling or pressing against the fabric.

A further object is to provide a structure of this character formed in one sheet with 20 the post and which can be cheaply manufactured.

With the foregoing and other objects in view, which will appear as the description 25 proceeds, the invention resides in the combination and arrangement of parts and in the details of construction hereinafter described and claimed, it being understood that, within the scope of what is claimed, changes in the precise embodiment of the invention shown can be made without departing 30 from the spirit of the invention.

In the accompanying drawing the preferred form of the invention has been shown.

In said drawing

35 Figure 1 is an elevation of a post embodying the present improvements, a portion thereof being broken away and the strands of the fence fabric being shown in section.

Fig. 2 is a section on line 2—2, Fig. 1.

40 Referring to the figures by characters of reference 1 designates the body portion of the post formed of sheet metal and of any desired cross sectional contour. In the structure shown this post is provided at its lower 45 end with angularly disposed tongues 2 terminating at their free ends in laterally curved points 3. Thus when the post is driven into the ground these points will curl upwardly and constitute anchors to prevent 50 withdrawal of the post from the ground.

Formed longitudinally along one edge of the sheet metal constituting the body portion of the post is a radial outstanding flange 4 provided, at desired intervals, with 55 longitudinal slots 5 and opening into the

middle portion of the outer side of each of these slots is a V-shaped slot 6 extending inwardly from the free longitudinal edge of the flange 4. Formed in the outer edge of each slot 5 at the ends of the slot are recesses 7 constituting seats for the strands of the fence fabric and which strands have been indicated at F.

After the posts have been set up for use the wire fabric constituting the fence is 65 stretched against the flanges 4 of the different posts and then pushed downwardly. This will cause the strands to move downwardly within the outer portions of certain of the slots 6. The fabric is then lifted up- 70 wardly and pressed inwardly so as to pass through the inner portions of the slots 6 and thus enter the longitudinal slots 5. Some of the strands of the fence fabric will become seated in the notches 7 at the upper 75 ends of the slots 5 while other strands will become seated within the notches at the lower ends of the slots. This will be apparent by referring to Fig. 1.

It will be obvious that after the fabric has 80 thus been placed in engagement with the flange 4 it becomes impossible for live stock to detach the fabric from the flange because, in order to do so, it is necessary to move the strands F from the ends of the slots 5 to the 85 inner end portions of the slots 6 and to then lift the said strands through the outer portions of the slots 6.

What is claimed is:—

A fence post comprising a sheet metal 90 body bent to form a tube, one edge portion of the body being extended radially to constitute a longitudinal flange, there being alined vertically spaced slots within the flange, each slot having a notch in its outer 95 wall adjacent each end forming a seat for a fence wire, there being an angular slot opening into each longitudinal slot at a point between the notches and opening through the free longitudinal edge of the flange, the end 100 portions of each angular slot diverging upwardly.

In testimony that I claim the foregoing as my own, I have hereto affixed my signature in the presence of two witnesses.

IRA E. CLUM.
